[57] CLAIM

The ornamental design for a differential pressure indicator, as shown and described.

DESCRIPTION

FIG. 1 is a top, front and right side perspective view of a differential pressure indicator showing our new design;

FIG. 2 is a bottom, rear and left side perspective view; FIG. 3 is a top plan view;

FIG. 4 is a right side elevational view, the left side elevational view being identical;

FIG. 5 is a typical end elevational view; and,

FIG. 6 is a bottom plan view thereof.
